UNITED STATES PATENT OFFICE.

GUY A. ZIMMEMAN, OF FOREST, OHIO, ASSIGNOR OF ONE-HALF TO DAVID L. COOK, OF FOREST, OHIO.

DESIGN FOR A CABINET.

54,297.

Specification for Design.

Patented Dec. 9, 1919.

Application filed June 30, 1919. Serial No. 307,867. Term of patent 7 years.

To all whom it may concern:

Be it known that I, GUY A. ZIMMEMAN, a citizen of the United States of America, residing at Forest, in the county of Hardin and State of Ohio, have invented a new, original, and ornamental Design for a Cabinet, of which the following is a specification, reference being had to the accompanying drawing, forming part thereof.

The figure is a perspective view of a cabinet showing my new design.

I claim:

The ornamental design for a cabinet, as shown.

GUY A. ZIMMEMAN. [L.S.]
